United States Patent Office

Des. 193,106
Patented June 26, 1962

193,106

STIFFENED NET FABRIC

Henry Zeeman, 1025 5th Ave., New York, N.Y.

Filed Nov. 8, 1960, Ser. No. 62,776

Term of patent 14 years

(Cl. D47—6)

The FIGURE is a plan view of a stiffened net fabric, showing my new design.

I claim:

the ornamental design for a stiffened net fabric, as shown.
